UNITED STATES PATENT OFFICE.

LAWRENCE W. MAMMEN, OF CHICAGO, ILLINOIS.

AIRSHIP.

Application filed August 26, 1925. Serial No. 52,553.

My invention relates to a dirigible air ship and has for its object the provision of a construction formed so as to automatically assist the lifting medium or gas in raising 5 the ship to the desired altitude; while at the same time providing a construction which will enable easy descent and alighting to be made.

One object of the invention is to provide 10 a construction adapted to withstand the enormous strains resulting from the high speed motors, the cargo or weight carried and those resulting from the continuous landings and upward pulls exerted when the ship 15 ascends; the invention involving a frame construction which will be comparatively light while at the same time possessing the necessary strength and rigidity; being so formed that all strains and stresses will be 20 transmitted to the trussed keel of the ship.

Another object of my invention is to provide 25 a construction which is so formed as to involve the principle of a parachute and which therefore will permit landings to be made in a more or less perpendicular or vertical direction so as to relieve the ship from 30 the usual jars and strains encountered in landing. The parachute portion of the ship involves controllable means whereby the 35 parachute effect or air resisting portion may be affected or manipulated so as to alter resistance to the air currents and thus place the air ship entirely within the control of the pilot.

The object and advantages of my improved air ship will be more readily comprehended and understood from the following detailed description of the drawings, 40 wherein:

Figure 1 is a perspective view of my improved air ship; with a portion of the outer covering or roof broken away and shown in section.

Figure 2 is a horizontal sectional plan 45 through the parachute portion thereof, namely the portion of the ship above the gas chambers.

Figure 3 is a vertical sectional view taken approximately along the longitudinal center line of the air ship.

Figure 4 is a horizontal sectional view taken substantially on the line 4—4 of Figure 3 looking in the direction of the arrows.

Figure 5 is a similar view taken substan-

tially on the line 5—5 of Figure 3 looking 55 in the direction of the arrows.

Figure 6 is a vertical sectional view taken on the offset line 6—6 of Figure 3 looking in the direction of the arrows.

Figure 7 is a detail sectional view taken 60 on the line 7—7 of Figure 6.

Figure 8 is a detail sectional view of the adjustable wing mounted on the deck of the air ship.

Figure 9 is a schematic elevation of that 65 portion of the air ship beneath the gas tanks or receptacles.

Figure 10 is a perspective view of a portion of the skeleton or frame of the air ship; parts of the frame members being broken 70 away and illustrating merely one end, as for example the forward end of the air ship.

Figure 11 is a sectional plan of the bottom of the air ship.

Figure 12 is a detail sectional view taken 75 on the line 12—12 of Figure 11.

Figure 13 is a detail sectional view taken at right angles to Figure 12.

My improved air ship contemplates a frame construction whereby all portions of 80 the air ship proper will be supported from the reenforced keel of the ship; the hull framework involving a specific construction whereby a plurality of compartments or spaces are provided, accessible from the 85 deck of the ship by means of hatchways; while the respective compartments permit passage from one to the other by means of suitable closures.

The framework consists of a suitable metallic keel 20, bowed to provide a ship-like hull adapted to float on water and reenforced with a truss 21 extending substantially throughout the length of the keel as shown in Figures 3 and 10. The truss involves 95 the struts or brace members 22 adjacent to the ends and the diagonally disposed struts 23 suitably connected at the ends to the keel proper which constitutes the chord of the truss, thereby providing a rigid structure 100 adapted to withstand strains and stresses.

In order that the frame may be constructed of comparatively light metal, I prefer to construct the keel proper in the form of an I-beam as shown at 24 in Figures 12 and 13; the web or intermediate portion thereof, at spaced intervals, being 105 provided with slots adapted to receive the

- laterally disposed rib members 25. The rib members 25, which are also formed out of comparatively light metal, for the purpose of strength, are in the nature of inverted 5 T-irons, as clearly shown in Figure 13 and pass through the corresponding slots formed in the web of the keel. The inverted head portions or laterally disposed flanges of the ribs are riveted or otherwise suitably secured 10 to the lower side flanges of the keel I-beam as shown at 26 in Figures 12 and 13. The ribs 25 are bowed, as shown in Figure 10, so as to provide a suitable bottom for the air ship and these ribs are preferably formed 15 to extend continuously about the air ship, with certain of the ribs constituting the supporting frame for the deck floor, namely the ribs 25^a, see Figure 10; while the ribs 25^b constitute a support for the ceiling of the 20 deck and therefore a support for the bottom of the gas chamber holding compartment; while some of the ribs are formed to extend over this gas chamber holding compartment, namely the ribs indicated at 25^c in 25 Figure 10; a fourth set being formed to provide support for the roof or parachute, namely the ribs 25^d; and a fifth portion or set of the ribs are formed to extend across the outside of the roof, namely the ribs indicated at 25^e in Figures 1 and 10. That is to say, the ribs are alternately formed of 30 different lengths so as to constitute the various portions just described, whereby all support and pulling strains are transmitted to 35 the keel proper.
- The portions of the ribs for supporting the ceiling, namely the ribs designated at 25^b, are also connected with a longitudinally disposed beam 27 extending full length and 40 at the longitudinal center line of the ship. The ends of the longitudinal beam 27 are connected with the ends of side frame members or ribs 28, which are bowed outwardly intermediate of the ends, where the ribs 25^b 45 are connected thereto. This ceiling frame, composed of ribs 25^b, longitudinal rib 27 and the two side bowed ribs 28, is also supported from the keel by the vertical members or posts 29.
- 50 The frame of the ship also consists of the outwardly bowed side rails 30 to provide the desired shape or contour to the ship; the side rails 30 being secured at their ends to the upwardly curved ends of the keel; and 55 the bottom frame portion of the ship also consists of the longitudinally disposed bottom rails 31 arranged in spaced relation with their ends preferably connected at the junction of the keel and side rails.
- 60 All of the rails are preferably formed of comparatively light metal and T-shape in cross section so as to have the necessary strength; the rails and ribs being bent by heat treatment, while the ends of the ribs 65 are preferably welded together to provide a

continuous one piece structure. The ribs are arranged and connected as described with the flat surfaces or head portions disposed outwardly so as to provide a flat surface or support for the sheet cover material. To afford proper support for the deck I show the lower portion of the frame, namely at a point below the main floor or deck of the ship, provided with arcuate braces 32, preferably also of T-shaped metal, see Figures 70 10 and 11, extending from points adjacent to the forward and rearward ends of the ship and bowed toward the truss 21 to which the intermediate portions are riveted or otherwise secured. 75

The air ship involves the hatch and lading receiving lower portion indicated generally at A in Figure 3, in which the engine or motors are also located; the deck portion indicated generally at B; the gas tank or chamber compartment or portion indicated at C; and the air chamber or portion indicated at D. It will be understood, of course, that the outer covering or walls may be of any suitable water resisting material and suitably secured to the frame members. The hatch or lower chamber A of the air ship is also shown provided with suitable tie rods or wires at 33 and this chamber or portion A at the ends is provided with suitable supporting frame members connected to the keel truss, to which the high speed motors generally indicated at 34 in Figures 3 and 5 are secured. The motors drive the propellers shown at 35 and provide power for operating and controlling the wings and other elements to be described and the motors are, of course, under the control of the operator from the pilot-house or chamber 36 located at the forward end of the air ship in the 100 deck compartment or portion. 95

The hatch A at suitably spaced intervals is preferably provided with partitions as at 37 to divide the hatch into a series of suitable chambers for the purpose of holding the lading in its predistributed manner so as to properly distribute the weight throughout the ship and maintain its equilibrium. The partitions 37 are preferably formed of heavy wire for the purpose of lightness; and the lading holding chambers are disposed on opposite sides of the longitudinal center line of the air-ship and accessible by hatchways indicated at 38 in Figure 6, from the deck of the ship; the hatchways being provided with ladders 39. 115

The deck portion B of the air ship is formed by the ribs 25^a to whose flat upper surfaces suitable plate or sheet material is secured; the deck being formed to provide a continuous open ended passage from front to rear of the ship; the forward end of the passage opening on opposite sides of the pilot house 36. This arrangement provides an air passage all the way through the ship 125 130

from the front to rear. The air ship on opposite sides of the longitudinal center line is shown provided with suitable cabins or state-rooms as shown at 40 in Figure 3, at 5 the rear or stern end of the ship and located in the spacing indicated at 40 in Figure 4. The side walls of the air ship extend a distance forward of the state-rooms 40, namely to the point indicated at 41 in Figure 4, 10 thus leaving openings on opposite sides of the pilot house 36 communicating with or constituting a portion of the continuous opening through the air ship; the air passage converging toward the rear end as 15 shown in Figure 4. This permits air to rush through the passageway and out through the rear end, discharging on opposite sides of the rudder indicated at 42 in Figures 3 and 4.

The ceiling of the deck portion B, at a 20 point just forward of the state-room chambers, namely at a point substantially one-third of the distance between the bow and stern, is given an upward bulge or arcuate formation as shown at 43 in Figure 3 to 25 provide an air pocket above the main part of the air passage. This pocket at 43 acts as a vacuum chamber when the air rushes through the passage way and tends to assist in the lifting of the air ship.

30 The portion of the air passage in vertical alignment with the vacuum pocket 43 is shown provided with a suitable number of wings or planes 44 arranged one above the other, as for example three, extending, preferably, entirely across the deck and two upper wings rigidly secured in place; the planes being bent downwardly toward the rear end at the regulation or proper angle as shown in Figure 3 in order that the air 40 rushing inwardly through the forward end of the air passage when encountering the wings 44 will assist in lifting the ship.

The ends of the upper wings may be secured to two of the ribs of the framework 45 and supported or braced in any suitable manner at intermediate points by means of the rods 44^a, see Figure 6, secured to the truss-work below the deck so that the lifting strain may be transferred to the keel and 50 main framework.

The lower wing 44^b is not fastened at its ends to the ribs of the ship, but has its forward edge hingedly secured in any suitable manner as at 44^c in order to permit this 55 wing to be tilted to varying degrees downwardly. The purpose of so mounting the lower wing is to offer greater resistance to the wind pressure through the deck passage, and thus assist in elevating the ship, without 60 the necessity for a long glide along the ground. At the same time, it is apparent that a downward tilt of the wing when alighting will also tend to provide a quick stop, without employing the parachute por-

tion of the ship, (later to be described) for 65 a vertical descent.

The upper compartment C of the air ship, namely above the ceiling of the deck proper, is provided with a number of independent gas chambers or tanks 45 preferably arranged in pairs on opposite sides of the longitudinal center line of the ship as shown in Figure 1, and arranged in spaced relation longitudinally of the ship so as to provide intervening air passages 46, see Figure 3. 70 These passages 46 extend from the air passage through the ship to the air chamber 47 immediately beneath the roof 48 of the ship. The chamber 47 extends throughout the entire upper portion of the air ship from 75 end to end and side to side as shown to form a parachute portion. The gas chambers or tanks 45 which are located on the ceiling are secured in place against any movement or shifting and are also held in 80 place by the supporting ribs 25^a, which extend across the tops of the tanks; and the tanks are shaped to conform to the upper portion of the ship adapted to offer as little 85 resistance as possible. Filling cocks for the tanks may extend through the ceiling of the ship so as to be easily accessible.

The ceiling portion of the deck at points in alignment with the vertically disposed air 90 passages 46, as well as the vacuum chamber 95 portion, are provided with series of openings as at 48 see Figures 2 and 3, in the nature of ventilators or air-tight closures. These ventilators are preferably all operatively connected together, see Figure 2, so that any one 100 or all of the series of ventilators 49 may be simultaneously opened or closed by suitable operating mechanism which may be under the control of the pilot; this mechanism being either mechanically, electrically or 105 otherwise operated.

The roof 48 of suitable light metal sheeting overhangs the sides of the air ship and connects with an extended portion of the ceiling and thus extends the parachute portion 47 beyond the sides of the main portion of the air ship as shown at 50 in Figures 1 and 2. This overhanging portion of the chamber 47 is provided with a number of 110 ventilators in the bottom as shown at 51 in Figures 1 and 2 disposed throughout the lower part of the overhanging portion of the air chamber 47. The ventilators 51 may have slidably mounted closure members all 115 operatively connected together by means of a suitable cable or chain as at 52 so that simultaneous operation of the ventilators may be had from a common point. The overhanging roof portion of the air ship may be properly supported by a suitable 120 number of tie rods or wires as at 53, see Figures 1 and 3, arranged at suitable intervals about the air ship; the lower end of the tie

wires being suitably connected to the lower or deck framework of the air ship.

The roof 48 at suitable intervals is shown provided with a number of vents as at 54 whereby air may gradually be permitted to escape from the parachute portion 47.

The air ship may be provided with any suitable number of propellers 35 both forward and aft; and the air ship at suitable points is shown provided with side wings or planes 55 of suitable construction and size, and preferably hingedly mounted as at 56, see Figures 1 and 6, so as to permit the wings 55 to fold upwardly against the sides 15 of the air ship. The pivotal point or hinge for the wings may be slidable on the bracket members 57 secured rigidly to the sides of the air ship.

The pivoted inner edge of each wing 55 may be controlled by means of a chain or cable 58 the ends whereof are secured to the wing or to its hinge connection; the chain in turn passing about the upper and lower pulleys 59 and 60 and about a suitable 25 windlass as at 61. The windlasses 61 at both sides of the ship may be operated by any suitable mechanism and preferably by means controlled from the pilot-house so that the wings may be separately operated 30 or both wings operated in unison. With the cables wound on the windlasses in one direction, the pivoted ends of the wings will be drawn down on the guide or bracket members 57 and held in place when the windlasses are locked against rotation; and the outer ends of the wings are maintained in place by means of the brace rods or arms 62, which are hingedly secured to the wings and to the sides of the ship.

40 The air ship is also shown provided at the forward or bow end of the ship with additional wings or planes as at 63, see Figure 1, preferably arranged at a point in alignment with the ceiling of the deck and therefore 45 just above the air passage through the air ship; while the rear or stern end of the ship is also shown provided with wings 64 one above the other, preferably arranged in pairs on each side of the rudder 42. The wings 50 of each pair are supported by any suitable frame, as at 65, with the frames of both pairs provided with an operating rod 66 which will permit simultaneous warping or 55 inclination of the wings 64; the operating rod 66 being controllable from the pilot house by any suitable operating mechanism not shown.

60 The movable wing 44^b located on the deck may be controlled by any suitable mechanism controllable from the pilot-house, as for example by means of a chain or cable 67 secured to the rear lower edge, (see Figure 8) and a chain or cable 68 secured to the upper rear edge; the cables in turn passing about 65 properly supported pulleys 69, above and be-

neath the deck and leading to control mechanism in the pilot-house.

In order to permit tilting of the wing, it is shown provided with enlarged slots for passage of the posts 44^a; and a suitable 70 guide-way for the rear edge of the wing may be provided as shown for example at 70 in Figure 3.

It is apparent that when the propellers 35 are rotating at full speed, downward tilting 75 of wing 44^b to a proper degree will cause rapid ascent of the air ship.

The two elevating planes 63 at the forward end, like the planes 64 at the rear end, are hingedly secured in place and all of the 80 planes or wings are preferably operatively connected by suitable operating mechanism, not shown, so as to permit simultaneous operation from the pilot-house.

The hull of the ship is shown provided with closable port-holes 71; and the bottom is preferably provided with suitable yieldably mounted skids 72, see Figures 3 and 6. While my air ship is especially designed to alight on and ascend from water, the skids held by means of springs will permit landing on a flat surface such as ice.

The upwardly bent portion 43 of the ceiling provides a vacuum, or semi-vacuum, as the air rushes through the passageway, which it is believed will assist in ascending. The upper part of this pocket 43, like other portions of the ceiling, is provided with the controllable ventilators 49. These ventilators are opened up so as to permit air to 100 enter the chamber or compartment C above the ceiling and thus bring the parachute portion of the ship into play when descent in a perpendicular manner is desired; the parachute portion being provided as a means 105 of safety to permit a gradual descent to be made. The vents 54 in the roof or top of the ship retard the outflow as these vents have relatively small openings for air escape.

The outside thin metallic covering of the 110 ship, provides suitable protection for the gas retainers, which may be of silk or other light material, as these retainers or bags will not be exposed to the elements.

The openings, at front and rear, of the 115 passageway across the deck may be closed by means of canvas shutters or curtains wound on vertically disposed rollers as for example shown at 73 in Figure 1; the canvas being provided with stiffening slats or rods 120 whose ends may ride in suitable grooves above and beneath the curtain; the free ends of the curtains to be fastened in any suitable manner so as to maintain them in passage closing position when desired.

125 It is apparent that the specific embodiment of the invention as disclosed in the drawings may be modified, as for example the number of wings mounted on the deck in the air passageway may be changed; the 130

number and placing of the ventilators may be altered; and modifications in certain other details of construction may be made without, however, departing from the spirit of my invention.

What I claim is:

1. An air ship, comprising a main or hull portion provided with a deck, side walls and a ceiling or top for the deck, the walls being formed to provide an air passage from end to end of the ship, an offset or pocket formed in the ceiling intermediate of the ends of the passage to constitute a vacuum chamber.

2. An air ship, comprising a hull portion provided with a deck, the side walls of the hull portion extending above the deck and supporting a ceiling or covering for said deck, the fore and aft portions of the ship above the deck and beneath the ceiling being open to provide an air passage lengthwise of the ship, with the ceiling or covering at a point intermediate of the front and rear provided with an upward bulge extending transversely of the ship to provide a vacuum chamber communicating with said air passage.

3. An air ship, comprising a hull portion provided with a deck, the side walls of the hull portion extending above the deck and supporting a ceiling or covering, the fore and aft portions of the ship above the deck and beneath the ceiling being open to provide an air passage lengthwise of the ship, with the ceiling or covering at a point intermediate of the front and rear provided with an upward bulge extending transversely of the ship to provide a vacuum chamber communicating with said air passage, and rearwardly declining wings arranged in said air passage.

4. An air ship, comprising a hull portion provided with a deck, the side walls of the hull portion extending above the deck and supporting a ceiling or covering for said deck, the fore and after portions of the ship above the deck and beneath the ceiling being open to provide an air passage lengthwise through the ship, propellers arranged at the bow and at the stern of the ship, and a laterally movable rudder or vertically disposed wing arranged at the stern of the ship in alignment with said air passage.

5. An air ship, comprising a hull portion provided with a deck, the side walls of the hull portion extending above the deck and supporting a ceiling or covering, the fore and aft portions of the ship above the deck and beneath the ceiling being open to provide an air passage lengthwise of the ship, the ceiling or covering at a point intermediate of the front and rear being provided with an upward bulge extending transversely of the ship to provide a vacuum chamber communicating with said air passage, and a plurality of rearwardly declining wings spaced

ly secured one above the other in said air passage.

6. In an air ship, a frame comprising a keel having transverse slots therethrough, and ribs disposed transversely through said slots, the keel and ribs adjacent to the slots being rigidly secured together.

7. In an air ship, a frame comprising a keel consisting of an I-beam having transverse slots through the web portion thereof, and transversely disposed ribs, T-shape in cross section, extending through the slots in the keel and rigidly secured thereto.

8. In an air ship, a frame comprising a keel consisting of an I-beam having transverse slots through the web portion thereof, and transversely disposed ribs, T-shape in cross section, disposed through the slots in the keel and rigidly secured thereto, the ribs consisting of continuous single piece members to provide a portion of the hull and deck supporting members extending continuously about the ship.

9. In an air ship, a frame comprising a keel consisting of an I-beam having transverse slots through the web portion, and transversely disposed ribs, T-shape in cross section, disposed through the slots in the keel and rigidly secured thereto, the ribs consisting of continuous single piece members, with all of the ribs forming a portion of the hull while certain of the ribs form deck supporting members and others form ceiling or covering supporting members, all of the ribs extending continuously about the ship.

10. An air ship, comprising a main or hull portion provided with a deck, the side walls of the hull portion extending above the deck about the ship, a ceiling above the deck and beneath the top of the ship so as to provide a compartment between the ceiling and the top of the ship, gas holding receptacles mounted in said compartment in spaced relation with each other and with the top of the ship to provide an air chamber, and means for controlling admission of air to said chamber.

11. In an air ship, a frame comprising a keel having transverse slots therethrough, a truss disposed above and lengthwise of the keel and secured thereto, bowed side ribs secured at their ends to the ends of the keel, and ribs disposed transversely through the keel slots and secured thereto and to the side ribs.

12. In an air ship, a frame comprising a keel consisting of an I-beam having transverse slots through the web thereof, bowed side ribs or rails secured at their ends to the ends of the keel, a vertically disposed truss above the keel, extending lengthwise thereof and secured to the keel, horizontally disposed trusses or bowed brace members on each side of the median line of the ship with the ends

secured to the side rails while the intermediate bowed portions are secured to the vertically disposed truss, and transversely disposed ribs extending through the keel slots and secured thereto.

13. In an air ship, a metallic frame comprising a keel having transverse slots therethrough, a vertically disposed truss above and extending lengthwise of the keel and secured thereto, bowed side rails secured at their ends to the ends of the keel, and ribs disposed transversely through the keel slots consisting of continuous members throughout, certain of said ribs constituting deck supports, a second portion constituting ceiling supports, a third portion constituting gas receptacle holders, a fourth portion constituting top or roof supports, while a fifth portion is disposed across the top or roof.

14. In an air ship, a metallic frame comprising a keel consisting of an I-beam having transverse slots therethrough, and ribs consisting of T-bars disposed transversely through said keel slots with the heads of the T-bars secured to the flanges of the I-beam, all of said ribs extending continuously about the ship but into different horizontal planes to constitute, respectively, deck, ceiling and roof or top supports.

15. An air ship, comprising a hull portion provided with a deck, a ceiling portion above the deck, a top or covering arranged above in spaced relation with the ceiling to provide a gas receptacle holding compartment, side walls extending about the ship from hull to top, and an air passage lengthwise of the deck open at front and rear of the ship.

16. An air ship comprising a hull portion provided with a deck, a ceiling portion above the deck provided with an upward bulge at a point between the front and rear ends, a top covering above the ceiling in spaced relation therewith to provide a gas receptacle holding compartment, side walls extending about the ship from hull to top except at the front and rear so as to provide an air passage lengthwise of the deck, and regulable means for admitting air into the compartment above the ceiling.

17. An air ship, comprising a hull portion provided with a deck, a ceiling portion above the deck provided with an upward bulge at a point between the front and rear ends and extending transversely of the ceiling, a top covering above the ceiling in spaced relation to provide a compartment extending throughout the length and width of the ship, gas holding chambers arranged in spaced relation in said compartment, regulable means in the ceiling for admitting air into said compartment, and side walls formed so as to provide an open ended air passage extending lengthwise of the deck.

18. An air ship, comprising a hull portion

provided with a deck, a ceiling portion above the deck provided with an upward bulge intermediate of the front and rear and disposed transversely of the ship, downwardly sloping planes fixedly secured intermediate of the deck and the ceiling and beneath said bulge, a top covering above the ceiling in spaced relation to provide a compartment extending through the length and width of the ship, the ceiling and top covering extending beyond the side walls of the ship so as to have said compartment over-hang the normal sides of the ship, and regulable means in the overhanging portion of the ceiling for admitting air into said compartment.

19. An air ship, comprising a hull portion provided with a deck, a ceiling above the deck, a top covering above the ceiling in spaced relation to provide a chamber therebetween extending through the length and width of the ship, an open ended air passage extending lengthwise of the ship beneath the ceiling, the ceiling and top covering overhanging the main sides of the ship, regulable means arranged in the overhanging portion of the ceiling for admitting air to said chamber and means in the top covering for slowly discharging the air from said chamber.

20. An air ship, comprising a hull portion provided with a deck, a ceiling above the deck, a top covering in spaced relation above the ceiling to provide a closed chamber having vent openings in the top, the front and rear ends of the ship being open to provide an open ended air passage above the deck, regulable means in the ceiling for admitting air to said chamber, a rudder arranged in alignment with the rear end of said air passage, vertically spaced planes arranged in pairs on each side of the rudder, wings secured to each side of the ship, and propellers forward and aft.

21. An air ship, comprising a hull portion provided with a deck, a ceiling above the deck, a top covering in spaced relation above the ceiling to provide a closed chamber, regulable means for admitting air to said chamber, gas holders fixedly secured in said chamber so as to leave air passages therebetween and beneath said top covering, a pilot-house arranged at the bow of the ship while the walls of the ship between the deck and the ceiling and on opposite sides of the pilot house are open, passenger compartments at the rear end of the ship on opposite sides of the median line so as to provide a passage lengthwise of the ship open at the stern end and connecting with the openings on both sides of the pilot-house, and propellers at the front and rear ends of the ship.

22. An air ship, comprising engine and cargo holding hull portion provided with a deck, a pilothouse on said deck at the bow end, passenger compartments at the rear end

- of the deck on opposite sides of the median line, an open ended air passage lengthwise of the deck, gas receptacle holding compartment above the deck extending full 5 length of the ship and overhanging the sides thereof, regulable means for admitting air into the bottom of said last mentioned compartment, wings hingedly secured to the sides of the ship, means for holding the 10 wings in operative position, and propellers arranged at the fore and rear ends of the ship.
23. An air ship, comprising engine and cargo holding portion provided with a deck, 15 means for holding the cargo in fixed position relative to the median line and fore and aft parts of the ship, a pilothouse on the deck at the bow end, passenger compartments at the rear end of the deck on opposite 20 sides of the median line to provide an air passage lengthwise of the ship open on opposite sides of the pilot-house and open at the stern end of the ship, a gas receptacle holding compartment above the deck extending full 25 length of the ship and overhanging the sides thereof, regulable means for admitting air into the bottom of said compartment, means operable from the pilothouse for controlling said regulable means, a rudder in alignment with the rear end of 30 said air passage, and planes or wings arranged on opposite sides of the rudder, along the sides and at the forward end of the ship.
24. An air ship, comprising a hull portion 35 provided with lading holding compartments communicating with each other and accessible from above, a deck portion open at front and rear to provide an air passageway lengthwise of the ship, wings mounted one 40 above the other and disposed transversely of the deck, at least one of said wings being tiltable to different inclinations, a chamber above the deck extending throughout the length and width of the ship, gas holding 45 receptacles secured within said chamber in spaced relation, and controllable air admitting openings in the bottom of said chamber.
25. An air ship, comprising a frame structure whereby hull, deck and parachute portions are provided, an outer covering disposed entirely about the frame work to enclose all of said portions, said covering being formed to provide large air admitting 55 openings at front and rear of the ship, means whereby said openings may be closed, controllable means for admitting air to the parachute portion, and gas holding receptacles mounted in said parachute portion.
26. In an air ship provided with a deck 60
- having a ceiling or covering provided with a transversely disposed vacuum pocket at a predetermined distance from the front of the ship, and wings arranged one above the other, transversely of the deck and beneath said vacuum pocket, one of said wings being tiltable downwardly toward its rear edge to different inclinations, and means for controlling and holding said wing in its adjusted positions.
27. An air ship, comprising a framework composed of a reenforced keel and ribs disposed transversely of and secured to the keel, said ribs being continuous about the ship with their ends secured together and arranged to provide a hull portion, a deck portion, a parachute portion above the deck portion, an outer covering about the entire outer framework with closable port-holes in the hull portion and openings at front and rear substantially co-extensive with the width of the deck to provide an air passage lengthwise of the ship, a pilot-house on the deck at the bow of the ship and cabins on the deck toward the stern of the ship and on each side of the air passage, controllable air admitting openings in the bottom of the parachute portion, wings on both sides, at the front and at the rear of the ship, the wings at the rear being arranged in pairs on opposite sides of the median line of the ship, a rudder intermediate of said pairs of wings, and propellers, the air admitting openings of the parachute portion, the wings and the propellers all being controllable from the pilot house.
28. An air ship comprising a hull portion provided with a deck, a ceiling above the deck, a gas tank holding chamber above the ceiling, an outer covering above the hull portion and above the ceiling to form a roof for said gas tank holding chamber, the ship at front and rear being open between the deck and the ceiling to provide an air passage lengthwise of the ship beneath said ceiling, propellers for driving the ship, and controllable wings secured to the front and rear of the ship.
29. In an air ship, a closed hull portion provided with a deck, an outer covering arranged above the deck to provide a closure for the sides, the ship above the deck being open at bow and stern to provide an air passage lengthwise of the deck, wings mounted one above the other transversely of the deck at a point intermediate of the bow and stern, at least one of said wings being tiltable to different inclinations, and means whereby the tiltable wing may be held in position.
